UNITED STATES PATENT OFFICE

2,455,064

SPECIAL PURPOSE FILE

George L. Johnson, Detroit, Mich., assignor of
one-fourth to Fred J. Heideman, Detroit, Mich.

Application October 4, 1944, Serial No. 557,167

2 Claims. (Cl. 29—78)

1

This invention relates to cutting files particularly suited to use on parts so installed as to be difficult of access, as for example the contact points of many types of switches.

An object of the invention is to form a file with a working end portion bent at a considerable angle to the file body and thus suited for use in restricted spaces not accessible to a straight file.

Another object is to dispose a working end portion of a file in a plane transverse to the file body, and to adapt such end portion for selective angular adjustments in such plane to suit the tool to different jobs involving difficulty of access.

A further object is to provide for the interchangeable use on a file body of a variety of working end portions each suited to a different type of work or material.

These and various other objects are attained by the construction hereinafter described and illustrated in the accompanying drawing, wherein:

Fig. 1 is a plan view of a simplified form of my improved file.

Fig. 2 is a side view of the same.

Fig. 3 is a view of the handle-forming end of the file.

Fig. 4 is a view of the working end of the file.

Fig. 5 is a side view of a modification of the file adapted for adjustment.

Fig. 6 is an end view of the same.

Fig. 7 is an end view of a working member applicable to the adjustable file to replace that shown in Figs. 5 and 6.

Referring now in greater detail to said views, and describing first the construction illustrated in Figs 1-4, the reference character 1 designates an elongated file whereof an end portion 2 is preferably non-serrated and has its edges rounded to serve as a handle. The opposite end portion of the file is bent transversely to the file body or approximately so, as indicated at 3. Both side faces of the portion 3 are formed with cutting serrations and the face of the file body remote from the portion 3 is also preferably serrated as best appears in Fig. 1.

Because of its bent working end portion, said file can be readily used in many places not accessible to a straight file, either or both of the serrated faces of said end portion being employed.

The adjustable file illustrated by Figs. 5-7 comprises a body 4 and a working end portion 5 disposed transversely to such body. To adapt said body to adjustably and detachably carry the end portion 5, an end portion of the body is bent, as indicated at 6 transversely to the body or ap-

2

proximately so, and is return-bent upon the portion 6, as indicated at 7. The portion 7 extends preferably somewhat beyond the body 4 and is then return-bent on itself a short distance as indicated at 8. A bolt 9 passes through the portions 6 and 7 and together with a nut 10 serves to clamp the member 5 to said portions, and said member has an arcuate toothed end 11 which meshes with the similar free end of the body portion 8, the centers of the arcs being at the bolt axis and rotation of the member 5 about the bolt being prevented by the intermeshed teeth. To permit of readily adjusting the member 5 about the bolt axis, when desired, said member has a slot 12 extending from its bolt-receiving opening to the end 11, said slot being narrower than said opening and suited to accommodate the bolt shank. Said shank, however, has an enlargement 13 close to its head 14, to fit the opening of the member 5 and normally prevent any escape of said member.

When it is desired to angularly adjust the member 5, as for example to the dash line position shown in Fig. 6, the nut 10 is loosened to an extent permitting withdrawal of the enlargement 13 from said member. The latter may then be shifted slightly lengthwise to disengage its toothed edge 11 from that on the file body, and may be swung to the desired angle. The toothed edges are then again interengaged and the bolt tightened. It is obvious that the member 5 may be removed completely, if desired, when the bolt has been loosened and shifted as described, and another member having different characteristics may be substituted. Thus the member 5a (Fig. 7) differs considerably in width from the member 5. The tool may comprise any desired number of different working members, and the difference may involve width, thickness, length, shape, or the particular type of cutting serrations. Thus the described file may be suited to a great variety of different jobs and to use on a variety of different metals or other materials. The provision for angular adjustment of the members 5 or 5a permits of the tool being accurately suited to differently restricted places.

In present practice, it is necessary in filing the points of numerous types of boxes switches to largely disassemble their mechanisms to permit use of ordinary files. The described file in either of its illustrated forms eliminates necessity for such disassembly and subsequent reassembly and will thus effect a valuable saving of time and labor.

What I claim is:

1. A file comprising an elongated body having a bent end portion, a working member having cutting serrations and having an end portion formed with an opening and with a slot more narrow than said opening extending to the end of said portion, a fastening element securing the working member to the bent end portion of said body and comprising a shank adapted to pass through said slot, said shank having an enlargement to fit said opening of the working member, and means on the working member and body for normally restraining the working member from pivotal movement on said fastening element, said element being adjustable lengthwise to disengage said enlargement from said opening and the working member then being releasable from said restraining means by shifting said member lengthwise to accommodate said fastening element in said slot.

2. A file comprising an elongated handle-forming bar having an end portion bent to one side of said bar and return-bent to extend to the opposite side of the bar, a working member substan-

tially transverse to said bar and formed with cutting serrations, means pivoting said work member on said end portion to swing about an axis substantially parallel to and at one side of said bar, and means on said end portion at the other side of the bar for rigidly interlocking the working member with said end portion in selective angular positions with respect to said axis.

GEORGE L. JOHNSON.
